Primary Examiner — Stacia A Cadmus(74) *Attorney, Agent, or Firm* — Hogan Lovells US LLP(57) **CLAIM**

The ornamental design for a vehicle wheel rim, as shown and described.

DESCRIPTION

FIG. 1 is a front view thereof;

FIG. 2 is a perspective view thereof;

FIG. 3 is a top view thereof; and,

FIG. 4 is a rear view thereof.

In the drawings the broken lines depict environmental subject matter and form no part of the claimed design.
